HORIZONTALLY MOVABLE DAMPER

Charles Hennig, Freeport, N. Y., assignor to Morse
Boulger Destructor Company, New York, N. Y.,
a corporation of Delaware

Application January 17, 1951, Serial No. 206,369

6 Claims. (Cl. 126—285)

1

This invention relates generally to furnaces and in particular to damper structures therefor. The invention has special applicability to incinerators of the type disclosed in U. S. Patent No. 2,514,657, issued July 11, 1950.

The general object of the invention is to provide a novel, efficient, and easily installed and operated damper structure for the flue of a large furnace.

Herein a furnace of the incinerator type mentioned above, generally referred to as a destructor, has been adopted for the purposes of illustrating the applicability of the invention. Furnace installations of this class are commonly very massive, and the flue is accordingly of large cross section, requiring a damper of such size and weight that considerations of space and of handling are of extreme importance.

As a damper for the flue of a furnace of this class may be six or more feet in height, installation of the damper for vertical movement may even require breaking through the ceiling of the furnace room in which the destructor stands. This has been done heretofore in many such installations; but it is costly and otherwise undesirable. Thus an object of the present invention is to provide a novel structure wherein a damper may be operated horizontally so that extraordinary vertical range is unnecessary. Further the structure of the present invention obviates the employment of elevator machinery usually required to lift a heavy damper, for herein the damper always remains at the same level.

Another object is to provide a structure which may form a horizontal section of the flue of a destructor or other furnace, said section having a bay extending therefrom and a track extending across said section and into said bay, whereby the damper may be rollably mounted on said track and readily rolled back and forth between open and closed positions. Thus the effort required to open and close the damper is merely that necessary to roll it, such effort being obviously much less than required to raise it in the usual manner. Further the structure utilizes space at the level of the flue and thereby avoids any cutting through of a furnace room ceiling.

Where a heavy damper is merely to be rolled it will be plain that it may be opened and closed by manually operable means, and elevating machinery need not form a part of the furnace installation.

Another object of the invention is to provide such a structure having simple means for manual operation whereby an attendant may readily ad-

2

just the damper by pulling on one limb or the other of a catenary hanging conveniently above the furnace room floor.

These and other objects of the invention will be more fully understood from the following description and from the drawings, in which:

Fig. 1 is a side elevation of the structure embodying the invention;

Fig. 2 is a rear elevation;

Fig. 3 is a plan view;

Fig. 4 is the section 4—4 of Fig. 2;

Fig. 5 is an elevation of that side of the structure opposite to the side seen in Fig. 1;

Fig. 6 is the section 6—6 of Fig. 2; and

Fig. 7 is the section 7—7 of Fig. 2.

In Figs. 1 through 7, which relate specifically to the damper structure, the only portion of the destructor seen is an indication, in dotted lines, of the outline of the flue which the damper structure serves.

Referring now to the drawings in which like reference characters denote similar parts, the damper apparatus comprises a box, as best seen in Figs. 2 and 3, having two portions, 35 to the left in these figures, and 36 to the right. Portion 35 is actually the terminal section of flue 17 of the destructor and joins with the chimney of a building in which the destructor is installed. Portion 36 provides a bay protruding from the side of portion 35 and is adapted to house the damper 37 when the latter is in opened position. The damper is shown in closed (solid lines) and in opened (dotted lines) positions in Fig. 2.

The entire structure is supported by upright channels 38, 39, 40 and 41 (best seen in Fig. 3), mounted on a floor 42.

Portion 35 of the box is essentially a short conduit of rectangular cross section, as best seen in Fig. 2. The front of this conduit connects with the rear of flue 17, and the rear of the conduit with the entrance to the chimney of the furnace.

That side wall of portion 35 to the left in Figs. 2 and 3 is a plate 43; the side wall to the right comprises two plates, 44 and 45, as best seen in Figs. 3 and 5, the plates being separated to provide a doorway 46 between the two portions of the box through which the damper may be moved. Plate 43 is secured by suitable means, such as rivets 47 to the web of upright channel 38 (Fig. 1). Plate 44 is secured, as by rivets 48, to the web of upright channel 39; and plate 45 is secured, as by rivets 49, to the web of upright channel 41 (Figs. 3 and 6). Portion 35 is provided with a floor plate 50 (Fig. 2) which

is connected to the lower edge of plate 43 by an angle 51 and to the lower edges of plates 44 and 45 by a similar angle 52. The side wall plates 43, 44 and 45 are reinforced against buckling strains by angles 53, 54 and 55; and the floor plate 50 is reinforced by angles 56. Angles 54, 55 and 56 relating to side wall plates 44 and 45 are interrupted at doorway 46 (Fig. 6).

Portion 36 of the box is a bay or envelope for receiving the damper when the latter is in opened position as shown in dotted lines in Fig. 2. The front and rear walls of this portion comprise plates 57 and 58 respectively. The outer edge of each plate is suitably secured to a flange of upright channel 41. See Figs. 2, 3 and 5. The inner edges of the plates 57 and 58, where the two portions of the box are joined, are respectively secured as by rivets to a flange of upright channel 39, and to a flange of upright channel 40 (Figs. 3 and 5). A roof for portion 36 of the box is provided in the form of a horizontal channel 63 to the flanges of which the upper edges of the plates 57 and 58 are suitably secured. See Fig. 7. A bottom for the same portion of the box is provided by another channel 64 to the flanges of which the lower edges of the plates 57 and 58 are secured. Channels 63 and 64 extend from upright channel 41 to channels 39 and 40, as shown. Channel 41 seals the outer end of portion 36, so this portion is everywhere sealed except at doorway 46 communicating with portion 35.

At the upper edges of plates 43, 44 and 45 are two angles 65. A channel 66 bridges portion 35 of the box transversely, as best shown in Figs. 2 and 3, and is aligned with channel 63 (see Fig. 3, particularly). The ends of channel 66 are supported by angles 65 and one end is rigidly connected to channel 63 by means of a tie 67 (Figs. 2 and 3). The tie 67 is a short section of channel stock, and serves also as a hanger, like hangers 68, 69 and 70, for a trolley system described below.

Fig. 7 is the section 7—7 of Fig. 2 and is considerably enlarged to show structural details of part of the trolley system, which comprises, in part, a pair of opposed channels 71 and 72 which extend from hanger 68 to hanger 70 and are secured to the three hangers and the tie 67. Supported by and between channels 71 and 72 is a trolley track member 73, a cross section of which is seen in Fig. 7.

Rollably mounted within the track member 73 are four-wheeled trolleys 74 and 75 (see Figs. 2 and 3). Two wheels of each trolley are mounted on one side of the track member, and the other two wheels thereof on the other side of the member (Fig. 7). From each trolley depends, between the sides of the track member and the channels 71 and 72, a bolt. The bolt relating to trolley 74 is designated 76; that relating to trolley 75 is designated 77. A narrow plate 78 extends between bolts 76 and 77 and is suitably secured thereto by means of nuts 79. Mounted on the plate 78 between bolts 76 and 77 and secured thereto by nuts 80 are two hook bolts 81 and 82. The damper is provided with straps 83 and 84 at its upper corners, and the damper is suspended from the hook bolts and the trolleys by engagement of hook bolt 81 by strap 83 and by engagement of hook bolt 82 by strap 84, as best seen in Fig. 2.

Rotatably mounted on channel 66 is a pocketed sheave 85; and similarly mounted on the outer end of portion 36 of the box is a like sheave 86.

It will be noted on Fig. 3 that channel 66 is slotted to accommodate sheave 85, and that channel 63 is slotted to accommodate sheave 86. Attached to plate 78 at 87 is a chain 88 which passes around sheave 85, extends to and around sheave 86 and back to the plate 78 at its ends 87 and 89.

The shaft 90 of sheave 86 is extended forwardly, as shown in Fig. 3, and also mounted on this shaft in front of portion 36 of the box, is another and larger sheave 91. Mounted on sheave 91 is an endless chain 92 (Figs. 2 and 3), the catenary 93 of which may be conveniently utilized in usual manner to rotate the sheaves and so move the trolley and damper back and forth from one portion of the box to the other, as shown in Fig. 2. Accordingly the damper door 37 may be readily moved to close or to open the flue completely or to any desired adjusted position between fully closed and fully open position.

The terms and expressions which have been employed herein are used as terms of description and not of limitation, and there is no intention in the use of such terms and expressions of excluding any equivalent of the features shown and described or portions thereof, but it is recognized that various modifications are possible within the scope of invention claimed.

What is claimed is:

1. In a flue, an enclosed bay to the side of said flue, a doorway between said flue and bay, a trolley track mounted in and enclosed by said flue and bay and extending through said doorway, a plurality of wheeled trolleys mounted on said track, a bolt depending from each of said trolleys, an elongate plate secured to said bolts, a damper suspended from said plate, and means for rolling said trolleys on said track, including a first grooved sheave rotatably mounted in said flue and a second grooved sheave rotatably mounted in said bay, and a chain trained from said trolley over both sheaves and having one of its ends secured to one end of said plate and its other end to the other end of said plate back to said trolley, links of said chain being received in the grooves of said sheaves, and mechanism for rotating said second sheave.

2. In a furnace flue, a horizontal section having an enclosed bay extending from one side thereof; a trolley track extending across said section and into said bay; a trolley mechanism rollably mounted on said track; a damper door suspended from said trolley mechanism; a first sheave mounted on said section and a second sheave mounted on said bay; said trolley mechanism including two spaced apart sets of wheels; each set having a bolt depending therefrom, an elongate plate secured to the lower ends of said bolts and providing means on which to hang said door; a chain extending from one end of said plate over both sheaves and back to the other end of said plate; and means for rotating one of said sheaves whereby said chain is driven to effect movement of said trolley mechanism on said track to move said damper door to open and to closed position in said flue.

3. In a furnace flue, a horizontal section having an enclosed bay extending from one side thereof and having a doorway into said enclosed bay; a trolley track extending across said section and into said bay and enclosed therein; a trolley rollably mounted on said track; a damper door suspended from said trolley; a first sheave mounted on said section and a second sheave mounted on said bay; a chain extending from said trolley over both sheaves and back to said

trolley; and means for rotating one of said sheaves whereby said chain is driven to effect movement of said trolley to move said damper to open and to closed position in said flue, said means comprising a third sheave coaxial with said second sheave and adapted to rotate therewith, and an endless chain mounted on said third sheave for manual actuation of said third sheave.

4. In a flue defined by two vertical and two horizontal walls; a damper-door housing extending laterally at right angles to said flue and having side walls, and a top, a bottom and an end wall, an open end opposite said end wall, a passageway in one of said vertical walls of said flue, the ends of said side, top and bottom walls of said housing being connected to said one of said vertical flue walls so that said open end is in registry with said passageway, thus providing a doorway for a damper door between the interior of said housing and said flue, a fixedly secured horizontal track crosswise of said flue and extending through said doorway into said housing, a plurality of wheeled trolleys having wheels rollable on said track, damper door suspending members depending from said wheeled trolleys, a damper door suspended on said members and movable through said doorway, a sheave mounted for rotation in said flue adjacent one end of said track, a sheave mounted for rotation in said housing adjacent the other end of said track, a chain trained over said sheaves and secured to said damper door, and operative upon rotation of one of said sheaves in one direction to move said trolleys along said track thereby carrying said damper door through said doorway into said flue and in the other direction to move said trolleys in the opposite direction along said track thereby carrying said damper door through said doorway into said housing, and means for rotating one of said sheaves.

5. In a flue defined by two vertical and two horizontal walls; a damper-door housing extending laterally at right angles to said flue and having side walls, and a top, a bottom and an end wall, an open end opposite said end wall, a passageway in one of said vertical walls of said flue, the ends of said side, top and bottom walls of said housing being connected to the vertical flue wall which has said passageway so that the open end is in registry with said passageway, thus providing a doorway for a damper door between the interior of said housing and said flue, a fixedly secured horizontal track crosswise of said flue and extending through said doorway into said housing, a plurality of wheeled trolleys having wheels rollable on said track, a bolt depending from each of said wheeled trolleys, a narrow plate secured to the lower ends of said bolts, a damper door suspended from said plate and movable through said doorway, a rotatable sheave mounted for rotation adjacent each end of said track, a chain trained over said sheaves and having its ends secured to said plate, whereby upon rotation of one of said sheaves in one direction said trolleys roll along said track and carry said damper door through said doorway.

way into said flue and upon rotation of that sheave in the opposite direction said trolleys roll along said track in said opposite direction and carry said damper door through said doorway into said housing, and means including a third sheave and manually operated means for rotating one of said first mentioned sheaves in the other direction to move said trolleys in the opposite direction along said track thereby carrying said damper door through said doorway into said housing.

6. In a flue defined by two vertical and two horizontal walls; a damper-door housing extending laterally at right angles to said flue and having vertical side walls, and a top, a bottom and an end wall and an open end opposite said end wall, a passageway in one of said vertical walls of said flue, the ends of said side, top and bottom walls of said housing being connected to the vertical flue wall which has said passageway with its open end in registry with said passageway, thus providing a doorway for a damper door between the interior of said housing and said flue, a fixedly secured horizontal track within and crosswise of said flue and extending through said doorway into said housing adjacent the top wall of said housing, a plurality of wheeled trolleys having wheels rollable on said track, a bolt depending from each of said wheeled trolleys, a narrow plate secured to the lower ends of said bolts, damper-door hangers depending from said plate, a damper door movable through said doorway, upwardly extending reinforcing straps secured to said door and suspended from said hangers, a first sheave mounted for rotation in said flue adjacent one end of said track, a second sheave having a shaft extending beyond a side wall of said housing and mounted for rotation in said housing adjacent the other end of said track, a chain trained over said sheaves and secured to said plate and operative upon rotation of one of said sheaves in one direction to move said trolleys along said track thereby carrying said damper door through said doorway into said flue and in the other direction to move said trolleys in the opposite direction along said track thereby carrying said damper door through said doorway into said housing, a third sheave mounted on said shaft outside of said housing, and a chain accessible for manual operation trained over said third sheave for rotating said third sheave thereby to move said damper door to open and to closed positions.

CHARLES HENNIG.
